LASTING MACHINE

Philip E. Burby, Beverly, Mass., assignor to
United Shoe Machinery Corporation, Flemington, N. J., a corporation of New Jersey

Application October 5, 1943; Serial No. 505,023

58 Claims.

(Cl. 12—14)

This invention relates to lasting machines, and is herein illustrated as applied to a machine which, except as hereinafter noted, is constructed generally as disclosed in United States Letters Patent No. 2,160,846, granted on June 6, 1939; on an application of F. C. Eastman's and A. F. Pym's. That machine is a power-operated machine for lasting the toes of welt shoes. It should be understood, however, that the invention is not limited to machine organizations of that particular character, and that while it has important advantages as applied to toe lasting and to welt shoe work, in various novel aspects it is of more general applicability.

In toe-lasting machines, of which the above-mentioned machine is an example, it is the practice to use wipers shaped to conform to the contour of the edge of an insole pattern, or of what is sometimes termed a last bottom pattern, corresponding to a shoe of a given style and size. While this has been regarded as the best practical expedient, it will be evident that in operating on a shoe of that style and size the wipers, because of the added thickness of the upper materials, will not conform exactly to the contour of the upper opposite the edge face of the insole, nor on welt shoe work will they conform exactly to the contour of the upstanding margin of the upper which they press inwardly against the usual lip or shoulder on the insole located at some distance from its edge. In wiping the upper heightwise of the last, moreover, commonly known as the upwiping operation, the wipers usually will not conform so nearly to the shoe contour at a distance from the edge of the insole as adjacent to its edge. It is also the common practice, for the sake of economy, to use the same wipers in lasting shoes of several different sizes, and it will be evident that they will not fit some of the shoes so well as others. For shoes which differ substantially in style, and under some conditions also for those which do not differ very much as to size, different wipers are regarded as necessary, which adds considerably to the cost of machine equipment.

In view of the above and other considerations, an object of the present invention is to provide what may be termed universal wiping means or wipers, which will conform to the different contours of different portions of a shoe in the course of the lasting operation and also to the contours of shoes of different styles and sizes, thus contributing to better results in the lasting of the shoes and also saving the expense of a multiplicity of wipers. For the purposes in view, the construction herein shown comprises two groups of lasting members supported respectively by two holders which are movable relatively to each other to carry the groups of members inwardly about the end of the shoe, the members of each

group being arranged in a series lengthwise of the edge of the shoe bottom and being relatively movable to conform to the contour of the upper in wiping it heightwise of the last and also, on 5 welt shoe work, in pressing its margin inwardly against the lip or shoulder on the insole. Springs carried by the holders are arranged to urge the members individually in inward directions while permitting them thus to adjust themselves to the contour of the shoe. Since greater force is required in wiping the marginal portion of the upper inwardly over the insole, and especially in pressing its margin against a lip or shoulder on the insole, than in wiping it heightwise of the last, provision is afforded for rendering the springs less responsive to resistance of the upper after the upwiping operation, this being accomplished in the illustrative embodiment of the invention by frictional control of the lasting members. More particularly, mechanisms operative in response to the movements of the above-mentioned holders are provided for applying clamping pressure to the groups of lasting members thus to control them frictionally.

15 To adapt the lasting means for use on shoes which differ substantially in size, the invention further provides a novel construction such that a variably predetermined number of each group of lasting members may be utilized, the rest being maintained in idle locations in the lasting operation. For this purpose, in the construction herein shown, each group of members is adjustable relatively to its holder in directions lengthwise of the edge of the shoe bottom to position a 20 variable number of the members in idle locations beyond the end of the shoe lengthwise thereof, the holder having means for suitably guiding and controlling the members as they are thus adjusted.

25 Preferably, in accordance with a further feature of the invention, there is associated with the groups of lasting members a flexible band arranged to extend about the end of the shoe between the members and the upper for engaging 30 the upper in the lasting operation. This band is herein shown as made up of a plurality of thin resilient metal strips in superposed relation, thus providing a band of substantial thickness without undue sacrifice of flexibility, but the invention is not limited to that particular construction. As 35 illustrated, the band is anchored independently of the groups of members in a location substantially at the extreme end of the shoe and is further controlled at its ends beyond the groups of members by springs which tend to pull its ends in outward directions widthwise of the shoe. When the groups of members are adjusted as 40 above described for shoes of different sizes they are moved along the band, the latter being held

45

55

60

in proper relation to the members regardless of their adjustment.

The above and other features of the invention, including various novel details of construction and combinations of parts, will now be more particularly described with reference to the accompanying drawings and thereafter pointed out in the claims.

In the drawings,

Fig. 1 is a view partly in right-hand side elevation and partly in vertical section, showing the wiper-operating mechanism of the machine to which the present invention is herein illustrated as applied, together with a portion of the wiping means provided by the invention;

Fig. 2 is a view partly in plan and partly in section, showing a portion of the wiper-operating mechanism and the wiping means associated therewith, parts being broken away;

Fig. 3 is a perspective view showing a portion of the wiping band and of means whereby it is supported;

Fig. 4 is a section on the line IV—IV of Fig. 2, with certain parts omitted;

Fig. 5 is a section on the line V—V of Fig. 2;

Fig. 6 is a view similar to a portion of Fig. 5, but showing also the shoe and showing the parts as they are positioned after the wiping operations with the upstanding margin of the upper pressed inwardly against a lip on the insole;

Fig. 7 is mainly a central vertical section longitudinally of the shoe, showing the parts as they are positioned substantially at the beginning of the operation of wiping the upper heightwise of the last; and

Fig. 8 is a view similar to a portion of Fig. 2, but showing the parts as they are positioned at the same time in the operation of the machine as in Fig. 6.

In view of the disclosure in the previously mentioned Letters Patent, the present description will be confined to such portions of the machine as it is necessary to refer to for an understanding of the invention. The shoe, herein shown as one of the welt type having a lip *a* (Fig. 6) on the insole, is positioned for the toe-lasting operation by a member 2 (Figs. 7 and 8) which engages the bottom face of the toe end of the insole and in the operation of the machine on such a shoe engages also the inner face of the lip of the insole around the end and along the sides of the toe to assist in determining the position of the shoe and also to support the lip against inwardly directed pressure of the wiping means on the margin of the upper. The member 2 is supported on the lower end of a rod 4 from which it is detachable to permit differently shaped members to be used in operating on shoes of different styles or sizes. After the shoe has been presented by the operator in engagement with the member 2 and in proper relation thereto, it is clamped against this member by a toe rest 6 which is moved upwardly into clamping position substantially at the beginning of the cycle of power operations of the machine.

Similarly to the disclosure of the previously mentioned Letters Patent, the machine is provided with wiper-operating mechanism including a pair of wiper holders 8 which are, however, modified as hereinafter described for purposes of this invention, these wiper holders being supported on a wiper carrier 10 under a cover plate 12 on the carrier. The wiper holders are provided with depending curved ribs 14 which lie in a guideway 16 (Figs. 2 and 8) in the wiper car-

rier, the guideway being curved about an axis which is located substantially at the extreme toe end of the shoe as the upper is wiped heightwise of the last. The wiper carrier is supported for movements to advance and retract the wiper holders lengthwise of the shoe on a pair of links 18 which are spaced apart laterally of the shoe and only one of which is herein shown, and on a lever 20 located farther rearwardly in the machine than the links 18 and supported between its upper and lower ends on a fulcrum rod 22. The lever is provided at its lower end with a roll 24 engaged by a path cam 26 whereby the lever is operated to advance and retract the wiper carrier. The links 18 are connected at their lower ends to arms 28 fast on a rockshaft 30 to which also is secured a cam-operated arm 32 for swinging the wiper carrier upwardly about its connection with the lever 20 to wipe the upper heightwise of the last. In time relation to their advancing movements lengthwise of the shoe by the wiper carrier 10 and in the course of such movements the wiper holders 8 are swung inward laterally of the shoe, first to bring the wiping means into proper relation to the upper for the upwiping operation and thereafter to effect the wiping of the upper inwardly over the insole, by forward rectilinear movement of a slide 34 guided on the wiper carrier. In the construction herein shown this slide is connected positively to the wiper holders 8 by links 36. The slide 34 is operated, as more fully disclosed in the previously mentioned Letters Patent, through one or the other or both of two springs 38, 40 by a bell-crank lever 42 pivotally mounted on the wiper carrier 10, this bell-crank lever being connected by a link 44 to an arm 46 fast on a rockshaft 48 on which also is secured an arm 50 provided with a roll 52 engaged by a path cam 54. The springs 38, 40 may yield in response to resistance to the movements of the wiper holders in pressing the upstanding margin of the upper inwardly against the lip of the insole, and similarly means not herein shown but disclosed in the above-mentioned Letters Patent is provided for yieldingly controlling the lever 20 in forcing the wiper carrier 10 lengthwise of the shoe.

For purposes of this invention the wiper holders 8, instead of supporting a pair of wiper plates as heretofore, are provided each with a group of wiper fingers 58 which may be termed inclusively a wiper, the fingers of each group extending lengthwise in generally parallel relation to the shoe bottom and being arranged in a series along the edge of the shoe bottom in parallel contiguous relation to one another with end faces thereof toward the shoe. The fingers of each group thus arranged are relatively movable lengthwise to conform to the contour of the upper in wiping it heightwise of the last and also in pressing its margin thereafter inwardly against the lip of the insole. Each group of fingers is mounted on a slide 58 which is adjustable rectilinearly on the holder 8 in directions lengthwise of the edge of the shoe bottom to vary the number of fingers in use for shoes of different sizes, the slide being guided in its adjusting movements by a groove 60 in the holder into which extends a tongue 62 on the slide. Each slide 58 is provided with an upstanding wall 64 which confines the group of fingers on one side and another upstanding portion 66 (Figs. 1 and 2) which confines the group on the other side. It is held in adjusted position on the holder 8 by a clamping screw 68 (Fig. 5) which is threaded in it and

the lip than in the upwiping operation. For this (Fig. 2) in the holder, the screw having a knurled head positioned in an opening 72 provided in the wiper carrier 10 to permit the movement of the holder. It will be observed that as shown in the drawings several of the fingers 56 of each group are not in positions for use, these idle fingers being confined lengthwise between an upwardly extending wall 74 of the holder 8 and a parallel wall 76 of a block 78 which is secured on the holder. These walls extend in oblique relation to the path of movement of the slide 58, and accordingly movement of the slide in the direction to increase the number of fingers in use causes the wall 76 to deflect the idle fingers lengthwise in inward directions toward operative positions. To limit its inward movement each of the several fingers is provided with a downwardly extending lug 80 arranged to engage the slide 58 in a recess formed in the slide. The fingers of each group which are in positions for use are controlled each by a spring-pressed plunger 82 in engagement with the outer end of the finger, the plungers being mounted in the block 78 and having in enlarged portions thereof springs 84 abutting at their outer ends against a plate 86 on the block. Movements of the plungers in inward directions toward the shoe are limited by engagement of their enlarged portions with shoulders on the block. By reference to Fig. 4 it will be seen that the plungers 82 are arranged in three rows and are staggered in such manner that there is one plunger in position to control each finger 56 regardless of the number of fingers in use, the fingers extending in directions heightwise of the shoe far enough to be controlled by plungers in any of the three rows, and that there is no opportunity for the fingers to enter spaces between the inwardly projecting end portions of the plungers in the course of adjustment of the group of fingers. In the lasting operation the springs 84 are yieldable in response to resistance of the upper while urging the fingers individually inward toward the upper, thus permitting the fingers to adjust themselves to the contour of the upper in wiping it heightwise of the last and also in pressing its margin inwardly against the lip on the insole.

Preferably, as shown, there is associated with the groups of fingers 56 a flexible resilient band 88 arranged to extend lengthwise about the toe in engagement with the upper. This band may be made of any material suitable for the purpose in view, and is herein shown by way of example as a laminated band made up of three strips of thin spring steel. At the extreme end of the toe the three strips are secured together and to a block 90 by a pin 92 (Figs. 1 and 7), the block 90 being mounted on the wiper carrier 10 and held in fixed relation to the carrier by pins 94. It will be noted that the previously mentioned upstanding walls 74 of the holders 8 are recessed to receive this block when the holders are in their open positions (Fig. 2). The band 88 extends along the ends of the groups of fingers 56 and is partially overlapped above by portions of the fingers, as well as by a portion of the block 90, to support it firmly in pressing the upper down on the feather of the insole. Its lower edge is flush with lower faces 96 (Fig. 5) of inwardly projecting end portions of the fingers, and also with a lower face 98 (Fig. 7) of a projecting portion of the block 90; these faces of the fingers and the block serving in addition to the band as wiping faces in wiping the upper inwardly over the insole. Beyond the groups of fingers the band extends over curved

shoulders 100 on the inner ends of the walls 64 of the slides 58 and thence outwardly widthwise of the shoe to springs 102 which are connected at their inner ends to one of the three strips which make up the band and at their outer ends to pins 104 on the holders 8, only one of the springs being visible in the drawings. Near their outer ends the several strips are held in assembled relation by clips 106 which permit those portions of the strips to slip relatively to one another in lengthwise directions. The inner ends of the walls 64 partially overlap the top of the band similarly to the fingers 56 and the block 90, and also like this block are so formed as to provide lower faces (not shown) flush with the lower edge of the band. To assist in properly supporting the band in the wiping of the upper heightwise of the last, it has secured to it in locations at considerable distances from the end of the toe two blocks 108, one at each side of the toe, one of the blocks being shown in Figs. 3, 5 and 6. Each block has fast therein a pin 110 which is also fast in that strip of the band which is next to the upper in the upwiping operation and extends through slots 112 in the other two strips to permit relative lengthwise slipping movements of portions of the strips. The blocks are located in slots 114 in the fingers 56 which are in line therewith. Such slots are preferably provided in all the fingers, both for the sake of uniformity in manufacture and also to permit the groups of fingers to be adjusted for shoes of different sizes as hereinbefore described, and similar slots may extend part way through the walls 64. If desired, moreover, additional blocks 108 may be provided in locations nearer the end of the toe, although it is contemplated that ordinarily such additional blocks will not be needed, the intermediate portion of the band being fast on the block 90. It will be understood that as the groups of fingers are adjusted they move relatively to the blocks 108 and the latter enter the slots 114 of different fingers. Notwithstanding the presence of the slots, all the fingers which are in use engage the band in locations above and below the slots and press it inwardly against the upper.

It will be understood that the springs 102 by their outward pull on the ends of the band 88 hold it at all times against the shoulders 100 of the walls 64 and are yieldable to permit the groups of fingers 56 to be adjusted along the band for larger shoes. Since the intermediate portion of the band is fast on the block 90 secured to the wiper carrier 10, the band is held in proper relation to the ends of the fingers when the latter are in their initial positions as shown in Fig. 2. In the lasting operation the band and the fingers conform to the contour of the shoe, first in wiping the upper heightwise of the last and thereafter in pressing its margin inwardly against the lip of the insole, the springs 84 yielding more or less in response to resistance of the upper to the pressure applied thereto. In order that the upper will be properly shaped in the angle between the feather and the lip of the insole it is desirable to apply greater inwardly directed pressure to it in pressing its margin against the lip than in wiping it heightwise of the last, and greater force, moreover, is needed in wiping the marginal portion of the upper inwardly over the insole than in the upwiping operation. There is accordingly further provided means for rendering the springs 84 less responsive to resistance of the upper in wiping it inwardly over the insole and pressing its margin against

the lip than in the upwiping operation. For this purpose each group of fingers 56 is engaged on one side by a block 116 movably mounted in a recess in the upstanding portion 66 of the corresponding slide 58 for applying clamping pressure to the group of fingers, so that by reason of their frictional engagement with one another and with the wall 64 and the block 116 they will apply to the upper in wiping it inwardly over the insole and in pressing it against the lip the greater force desired, while still being relatively movable to permit them to adjust themselves to the contour of the upper against the lip. Each block 116 is engaged, in a curved recess formed therein, by the curved inner end of a lever 118 also located in the above-mentioned recess in the upstanding portion 66 of the slide 58 under a cover plate 120 thereon, the lever being pivotally mounted on a pin 122. Fast in the outer end of each lever 118 is a spring 124, which may be considered a part of the lever, the spring having a rearwardly extending end portion arranged to be engaged by one of the diverging arms of a V-shaped member 126 fastened by pins 128 to the wiper carrier 10. Initially the rear ends of the springs are spaced from the arms of the V-shaped member as shown in Fig. 2, and they are carried into engagement with the arms by the operative swinging movements of the wiper holders 8, after which further movements of the holders cause the levers 118 to be operated yieldingly through the springs to apply the clamping pressure to the fingers 56. The levers are thus operated, mainly at least, in response to those movements of the wiper holders which take place, after the upwiping operation, to wipe the marginal portion of the upper inwardly over the insole, at which time it is desirable to increase the force applied to the upper as above explained.

The machine shown in the previously mentioned Letters Patent is provided with a plurality of grippers for gripping the margin of the toe end of the upper and for applying a pull to the upper in time relation to the operation of the wipers. It has been proposed heretofore to use, instead of such grippers, a retarder which clamps the margin of the upper outspread on the wipers to control it in the lasting operation. It is contemplated that preferably, although not necessarily, the machine provided with wiping means such as herein disclosed will be equipped with a retarder instead of grippers, and such a retarder 130 is shown in Fig. 7, this being a retarder which, by way of example, is constructed and operated as disclosed in a copending application of mine, Serial No. 485,577, filed on May 4, 1943. This retarder clamps the upper mainly on the tops of the fingers 56 and the block 90 to control it as it is wiped heightwise of the last and at the beginning of the wiping of its marginal portion inwardly over the insole.

The manner of operation of the machine equipped with the wiping means herein shown, in so far as it is of interest with reference to the present invention, will now be briefly summarized. Early in the cycle of operations the wiper carrier 10 is advanced lengthwise of the shoe and the wiper holders 8 thereon are swung or closed inwardly about the toe into positions to render the wiping means effective on the upper in wiping it heightwise of the last, and the wiper carrier is swung upwardly to cause the wiping means thus to act on the upper. In this operation the band 88 and those fingers 56 which are in positions for use adjust themselves to the contour of the

upper about the toe in response to pressure of the upper thereon, the corresponding springs 84 which control the fingers through the plungers 82 yielding more or less to permit such conformity to the contour of the upper and serving as means through which pressure is yieldingly applied to the upper. During most of the upwiping operation also, and thereafter at the beginning of the wiping of the marginal portion of the upper inwardly over the insole, the retarder 130 assists in controlling the upper by clamping its margin outspread on the block 90 and the fingers 56 in a manner which will be more fully understood by reference to the previously mentioned application. The wiping of the upper inwardly over the insole is effected by further advancing movement of the wiper carrier 10 and closing movements of the holders 8. In response to such further closing movements of the holders the V-shaped member 126 acts yieldingly on the levers 118 through the springs 124 to apply clamping pressure to the groups of fingers 56, so that by reason of frictional engagement of the fingers with one another and with the clamping means the springs 84 become less responsive to the resistance of the upper. The upstanding margin of the upper, therefore, is pressed inwardly against the lip of the insole, which is backed up by the member 2, with greater force than is applied to the upper in the upwiping operation, yet at the same time the band and the fingers are permitted to adjust themselves to the contour of the upper against the lip, so that uniformly effective pressure is applied to all portions of the upstanding margin about the toe. In time relation to the inward wipe increased downward pressure also is applied to the upper over the feather of the insole through the band 88, the fingers 56 and the block 90 by downward movement of the wiper carrier 10. The completion of the toe-lasting operation, including the application of a binder wire to the margin of the upper, is then effected in the manner disclosed in Letters Patent No. 2,160,846, and the parts of the machine are returned to their starting positions.

In the appended claims the term "sole" is used generically to refer to an insole or other shoe bottom part over which the marginal portion of the upper is lasted.

Having described the invention, what I claim as new and desire to secure by Letters Patent of the United States is:

1. In a lasting machine, end-lasting means for wiping an upper about an end of a last heightwise of the last and then inwardly over a sole on the last, said end-lasting means comprising two groups of lasting members with the members of each group arranged in a series lengthwise of the edge of the shoe bottom and relatively movable rectilinearly in the lasting operation to conform to the contour of the upper in wiping it heightwise of the last, and two holders supporting said groups of members respectively and movable relatively to each other with the members thereon to effect the wiping of the upper inwardly over the sole.

2. In a lasting machine, end-lasting means for wiping an upper about an end of a last heightwise of the last and then inwardly over a sole on the last, said end-lasting means comprising two groups of lasting members with the members of each group arranged in a series lengthwise of the edge of the shoe bottom and relatively movable in the lasting operation to conform to the

contour of the upper in wiping it heightwise of the last, and holders each supporting one of said groups of members and movable with that group as a unit about an axis extending heightwise of the last to effect the wiping of the upper inwardly over the sole.

3. In a lasting machine, end-lasting means for wiping an upper about an end of a last heightwise of the last and then inwardly over a sole on the last, said end-lasting means comprising two groups of lasting members with the members of each group arranged in a series lengthwise of the edge of the shoe bottom and relatively movable in the lasting operation to conform to the contour of the upper in wiping it heightwise of the last, two holders supporting said groups of members respectively and movable relatively to each other with the members thereon to effect the wiping of the upper inwardly over the sole, and means on said holders arranged to control said members and yieldable in response to pressure of the upper on the different members individually to permit them thus to adjust themselves to the contour of the upper.

4. In a lasting machine, end-lasting means for wiping an upper about an end of a last heightwise of the last and then inwardly over a sole on the last, said end-lasting means comprising two groups of lasting members with the members of each group arranged in a series lengthwise of the edge of the shoe bottom and relatively movable in the lasting operation to conform to the contour of the upper in wiping it heightwise of the last, holders each supporting one of said groups of members and movable with that group about an axis extending heightwise of the last to effect the wiping of the upper inwardly over the sole, and springs on said holders arranged respectively to control said different members and yieldable in response to pressure of the upper on the members to permit them thus to adjust themselves to the contour of the upper.

5. In a lasting machine, end-lasting means for wiping an upper about an end of a last heightwise of the last and then inwardly over a sole on the last, said end-lasting means comprising two groups of lasting fingers with the fingers of each group extending lengthwise in generally parallel relation to the shoe bottom and arranged in a series along the edge of the shoe bottom in parallel relation to one another, the fingers of each group being relatively movable lengthwise in the lasting operation to conform to the contour of the upper in wiping it heightwise of the last, and holders each supporting one of said groups of fingers and movable with that group about an axis extending heightwise of the last to effect the wiping of the upper inwardly over the sole.

6. In a lasting machine, end-lasting means for wiping an upper about an end of a last heightwise of the last and then inwardly over a sole on the last, said end-lasting means comprising two groups of lasting fingers with the fingers of each group extending lengthwise in generally parallel relation to the shoe bottom and arranged in a series along the edge of the shoe bottom in parallel relation to one another, the fingers of each group being relatively movable lengthwise in the lasting operation to conform to the contour of the upper in wiping it heightwise of the last, two holders supporting said groups of fingers respectively and movable relatively to each other with the fingers thereon to effect the wiping of the upper inwardly over the sole, and springs on said holders arranged to control said fingers and yield-

able in response to pressure of the upper on the different fingers individually to permit them thus to adjust themselves to the contour of the upper.

7. In a lasting machine, end-lasting means for wiping an upper about an end of a last heightwise of the last and then inwardly over a sole on the last, said end-lasting means comprising two groups of lasting fingers with the fingers of each group extending lengthwise in generally parallel relation to the shoe bottom and arranged in a series along the edge of the shoe bottom in parallel relation to one another, the fingers of each group being relatively movable lengthwise in the lasting operation to conform to the contour of the upper in wiping it heightwise of the last, holders each supporting one of said groups of fingers and movable with that group about an axis extending heightwise of the last to effect the wiping of the upper inwardly over the sole, and spring-controlled plungers carried by the holders for engaging the different fingers respectively to control them in the lasting operation, said plungers being yieldable in response to pressure of the upper on the different fingers individually to permit the fingers thus to adjust themselves to the contour of the upper.

8. In a lasting machine, end-lasting means for wiping an upper about an end of a last inwardly over a sole on the last and for pressing its margin inwardly in upstanding position against a lip or shoulder on the sole, said end-lasting means comprising two groups of lasting members with the members of each group arranged in a series lengthwise of the edge of the shoe bottom and relatively movable in the lasting operation to conform to the contour of the margin of the upper pressed against said lip or shoulder, and holders each supporting one of said groups of members and movable with that group as a unit about an axis extending heightwise of the last to effect the wiping of the upper inwardly over the sole.

9. In a lasting machine, end-lasting means for wiping an upper about an end of a last inwardly over a sole on the last and for pressing its margin inwardly in upstanding position against a lip or shoulder on the sole, said end-lasting means comprising two groups of lasting members with the members of each group arranged in a series lengthwise of the edge of the shoe bottom and relatively movable in the lasting operation to conform to the contour of the margin of the upper pressed against said lip or shoulder, two holders supporting said groups of members respectively and movable relatively to each other with the members thereon to effect the wiping of the upper inwardly over the sole, and means on said holders arranged to control said members and yieldable in response to pressure of the margin of the upper on the different members individually to permit them thus to adjust themselves to the contour of the upper.

10. In a lasting machine, end-lasting means for wiping an upper about an end of a last inwardly over a sole on the last and for pressing its margin inwardly in upstanding position against a lip or shoulder on the sole, said end-lasting means comprising two groups of lasting fingers with the fingers of each group extending lengthwise in generally parallel relation to the shoe bottom and arranged in a series along the edge of the shoe bottom in parallel relation to one another, the fingers of each group being relatively movable lengthwise in the lasting operation to conform to the contour of the margin of the upper pressed against said lip or shoulder, and

holders each supporting one of said groups of fingers and movable with that group about an axis extending heightwise of the last to effect the wiping of the upper inwardly over the sole.

11. In a lasting machine, end-lasting means for wiping an upper about an end of a last inwardly over a sole on the last and for pressing its margin inwardly in upstanding position against a lip or shoulder on the sole, said end-lasting means comprising two groups of lasting fingers with the fingers of each group extending lengthwise in generally parallel relation to the shoe bottom and arranged in a series along the edge of the shoe bottom in parallel relation to one another, the fingers of each group being relatively movable lengthwise in the lasting operation to conform to the contour of the margin of the upper pressed against said lip or shoulder, two holders supporting said groups of fingers respectively and movable relatively to each other with the fingers thereon to effect the wiping of the upper inwardly over the sole, and springs on said holders arranged respectively to control said different fingers and yieldable in response to pressure of the margin of the upper on the fingers to permit them thus to adjust themselves to the contour of the upper.

12. In a lasting machine, end-lasting means for wiping an upper about an end of a last heightwise of the last and then inwardly over a sole on the last and for pressing its margin inwardly in upstanding position against a lip or shoulder on the sole, said end-lasting means comprising two groups of lasting members with the members of each group arranged in a series lengthwise of the edge of the shoe bottom and relatively movable in the lasting operation to conform to the contour of the upper in wiping it heightwise of the last and also in pressing its margin inwardly against said lip or shoulder, and holders each wholly supporting one of said groups of members and movable with that group about an axis extending heightwise of the last in the lasting operation.

13. In a lasting machine, end-lasting means for wiping an upper about an end of a last heightwise of the last and then inwardly over a sole on the last and for pressing its margin inwardly in upstanding position against a lip or shoulder on the sole, said end-lasting means comprising two groups of lasting members with the members of each group arranged in a series lengthwise of the edge of the shoe bottom and relatively movable in the lasting operation to conform to the contour of the upper in wiping it heightwise of the last and also in pressing its margin inwardly against said lip or shoulder, two holders supporting said groups of members respectively and movable relatively to each other to impart inward movements to the members in the lasting operation, and means on said holders arranged to control said members and yieldable in response to pressure of the upper on the different members individually to permit them thus to adjust themselves to the contour of the upper.

14. In a lasting machine, end-lasting means for wiping an upper about an end of a last heightwise of the last and then inwardly over a sole on the last and for pressing its margin inwardly in upstanding position against a lip or shoulder on the sole, said end-lasting means comprising two groups of lasting fingers with the fingers of each group extending lengthwise in generally parallel relation to the shoe bottom and arranged in a series along the edge of the shoe

bottom in parallel relation to one another, the fingers of each group being relatively movable lengthwise in the lasting operation to conform to the contour of the upper in wiping it heightwise of the last and also in pressing its margin inwardly against said lip or shoulder, holders each supporting one of said groups of fingers and movable about an axis extending heightwise of the last to impart inward movements to the fingers thereon, and springs on said holders associated respectively with the different fingers and yieldable in response to pressure of the upper on the fingers to permit the fingers thus to adjust themselves to the contour of the upper.

15. In a lasting machine, lasting means for wiping an upper heightwise of a last and then inwardly over a sole on the last, said lasting means comprising a plurality of lasting members arranged in a series lengthwise of the edge of the shoe bottom and relatively movable in the lasting operation to conform to the contour of the upper, means supporting said members and movable with them to effect the wiping of the upper inwardly over the sole, yieldable means carried by said supporting means for urging said members individually in inward directions, said yieldable means being responsive to resistance of the upper to permit the members to assume relative positions determined by the contour of the upper in wiping it heightwise of the last, and mechanism also carried by said supporting means for directly controlling said members to render said yieldable means less responsive to resistance of the upper in wiping it inwardly over the sole than in wiping it heightwise of the last.

16. In a lasting machine, lasting means for wiping an upper heightwise of a last and then inwardly over a sole on the last, said lasting means comprising a plurality of lasting fingers extending lengthwise in generally parallel relation to the shoe bottom and arranged in a series along the edge of the shoe bottom, said fingers being relatively movable lengthwise in the lasting operation to conform to the contour of the upper, means supporting said fingers and movable with them to effect the wiping of the upper inwardly over the sole, yieldable means carried by said supporting means for urging said fingers individually in inward directions, said yieldable means being responsive to resistance of the upper to permit the fingers to assume relative positions determined by the contour of the upper in wiping it heightwise of the last, and mechanism also carried by said supporting means for subjecting said fingers to lateral frictional control to render said yieldable means less responsive to resistance of the upper in wiping it inwardly over the sole than in wiping it heightwise of the last.

17. In a lasting machine, lasting means for wiping an upper heightwise of a last and then inwardly over a sole on the last, said lasting means comprising a plurality of lasting fingers extending lengthwise in generally parallel relation to the shoe bottom and arranged in a series along the edge of the shoe bottom, said fingers being relatively movable lengthwise in the lasting operation to conform to the contour of the upper, means supporting said fingers and movable with them to effect the wiping of the upper inwardly over the sole, springs carried by said supporting means and associated respectively with the different fingers for urging them in inward directions, said springs being responsive to resistance of the upper to permit the fingers to assume relative positions determined by the

contour of the upper in wiping it heightwise of the last, and mechanism also carried by said supporting means for applying clamping pressure laterally to said fingers to render said springs less responsive to resistance of the upper in wiping it inwardly over the sole than in wiping it heightwise of the last.

18. In a lasting machine, end-lasting means for wiping an upper about an end of a last heightwise of the last and then inwardly over a sole on the last, said end-lasting means comprising two groups of lasting members with the members of each group arranged in a series lengthwise of the edge of the shoe bottom and relatively movable in the lasting operation to conform to the contour of the upper, holders supporting said different groups of members respectively and movable with them to effect the wiping of the upper inwardly over the sole, yieldable means carried by said holders for urging said members individually in inward directions, said yieldable means being responsive to resistance of the upper to permit the members to assume relative positions determined by the contour of the upper in wiping it heightwise of the last, and means also carried by said holders for rendering said yieldable means less responsive to resistance of the upper in wiping it inwardly over the sole than in wiping it heightwise of the last.

19. In a lasting machine, end-lasting means for wiping an upper about an end of a last heightwise of the last and then inwardly over a sole on the last, said end-lasting means comprising two groups of lasting fingers with the fingers of each group extending lengthwise in generally parallel relation to the shoe bottom and arranged in a series along the edge of the shoe bottom, the fingers of each group being relatively movable lengthwise in the lasting operation to conform to the contour of the upper, holders supporting said different groups of fingers respectively and movable with them each about an axis extending heightwise of the last to effect the wiping of the upper inwardly over the sole, spring means carried by said holders for urging said fingers individually in inward directions, said spring means being responsive to resistance of the upper to permit the fingers to assume relative positions determined by the contour of the upper in wiping it heightwise of the last, and means also carried by said holders for subjecting said fingers to lateral frictional control to render said spring means less responsive to resistance of the upper in wiping it inwardly over the sole than in wiping it heightwise of the last.

20. In a lasting machine, end-lasting means for wiping an upper about an end of a last heightwise of the last and then inwardly over a sole on the last, said end-lasting means comprising two groups of lasting fingers with the fingers of each group extending lengthwise in generally parallel relation to the shoe bottom and arranged in a series along the edge of the shoe bottom in parallel contiguous relation to one another, the fingers of each group being relatively movable lengthwise in the lasting operation to conform to the contour of the upper, holders supporting said different groups of fingers respectively and movable with them each about an axis extending heightwise of the last to effect the wiping of the upper inwardly over the sole, springs on said holders associated respectively with said different fingers for urging them in inward directions, said springs being responsive to resistance of the upper to permit the fingers to assume relative positions

determined by the contour of the upper in wiping it heightwise of the last, and means on said holders for applying clamping pressure laterally to said groups of fingers to render said springs less responsive to resistance of the upper in wiping it inwardly over the sole than in wiping it heightwise of the last by reason of frictional engagement of the fingers with one another and with the clamping means.

21. In a lasting machine, end-lasting means for wiping an upper about an end of a last heightwise of the last and then inwardly over a sole on the last, said end-lasting means comprising two groups of lasting members with the members of each group arranged in a series lengthwise of the edge of the shoe bottom and relatively movable in the lasting operation to conform to the contour of the upper, holders supporting said different groups of members respectively and movable with them to effect the wiping of the upper inwardly over the sole, yieldable means carried by said holders for urging said members individually in inward directions, said yieldable means being responsive to resistance of the upper to permit the members to assume relative positions determined by the contour of the upper in wiping it heightwise of the last, mechanisms on said holders movable to render said yieldable means less responsive to resistance of the upper in wiping it inwardly over the sole than in wiping it heightwise of the last, and automatic means for thus operating said mechanisms after the wiping of the upper heightwise of the last.

22. In a lasting machine, end-lasting means for wiping an upper about an end of a last heightwise of the last and then inwardly over a sole on the last, said end-lasting means comprising two groups of lasting members with the members of each group arranged in a series lengthwise of the edge of the shoe bottom and relatively movable in the lasting operation to conform to the contour of the upper, holders supporting said different groups of members respectively and movable with them to effect the wiping of the upper inwardly over the sole, yieldable means carried by said holders for urging said members individually in inward directions, said yieldable means being responsive to resistance of the upper to permit the members to assume relative positions determined by the contour of the upper in wiping it heightwise of the last, mechanisms on said holders movable to render said yieldable means less responsive to resistance of the upper in wiping it inwardly over the sole than in wiping it heightwise of the last, and automatic means for thus operating said mechanisms after the wiping of the upper heightwise of the last.

23. In a lasting machine, end-lasting means for wiping an upper about an end of a last heightwise of the last and then inwardly over a sole on the last, said end-lasting means comprising two groups of lasting members with the members of each group arranged in a series lengthwise of the edge of the shoe bottom and relatively movable in the lasting operation to conform to the contour of the upper, holders supporting said different groups of members respectively and movable with them each about an axis extending heightwise of the last to effect the wiping of the upper inwardly over the sole, yieldable means carried by said holders for urging said members individually in inward directions, said yieldable means being responsive to resistance of the upper to permit the members to assume relative posi-

tions determined by the contour of the upper in wiping it heightwise of the last, mechanisms on said holders movable to control said members frictionally and thereby to render said yieldable means less responsive to resistance of the upper in wiping it inwardly over the sole than in wiping it heightwise of the last, and means supported independently of said holders for thus operating said mechanisms in response to the movements of the holders to wipe the upper inwardly over the sole.

24. In a lasting machine, end-lasting means for wiping an upper about an end of a last heightwise of the last and then inwardly over a sole on the last, said end-lasting means comprising two groups of lasting fingers with the fingers of each group extending lengthwise in generally parallel relation to the shoe bottom and arranged in a series along the edge of the shoe bottom in parallel contiguous relation to one another, the fingers of each group being relatively movable lengthwise in the lasting operation to conform to the contour of the upper, holders supporting said different groups of fingers respectively and movable with them each about an axis extending heightwise of the last to effect the wiping of the upper inwardly over the sole, spring means on said holders for urging the fingers individually in inward directions, said spring means being responsive to resistance of the upper to permit the fingers to assume relative positions determined by the contour of the upper in wiping it heightwise of the last, mechanisms including levers on said holders movable to apply clamping pressure laterally to said groups of fingers to render said spring means less responsive to resistance of the upper in wiping it inwardly over the sole than in wiping it heightwise of the last, and means for thus operating said levers in response to the movements of the holders to wipe the upper inwardly over the sole.

25. In a lasting machine, lasting means for wiping an upper heightwise of a last and then inwardly over a sole on the last, said lasting means comprising a plurality of lasting members arranged in a series lengthwise of the edge of the shoe bottom and relatively movable in directions generally parallel to the shoe bottom to adjust themselves to the contour of the upper in wiping it heightwise of the last, means supporting said members, and mechanism for automatically clamping said members on their supporting means after they have thus adjusted themselves to the contour of the upper.

26. In a lasting machine, lasting means for wiping an upper heightwise of a last and then inwardly over a sole on the last, said lasting means comprising a plurality of lasting fingers extending lengthwise in generally parallel relation to the shoe bottom and arranged in a series along the edge of the shoe bottom in contiguous relation to one another, said fingers being relatively movable lengthwise to adjust themselves to the contour of the upper in wiping it heightwise of the last, and mechanism for automatically clamping said fingers together after they have thus adjusted themselves to the contour of the upper.

27. In a lasting machine, end-lasting means for wiping an upper about an end of a last heightwise of the last and then inwardly over a sole on the last, said end-lasting means comprising two groups of members with the members of each group arranged in a series lengthwise of the edge of the shoe bottom and relatively movable in directions generally parallel to the shoe bottom to

adjust themselves to the contour of the upper in wiping it heightwise of the last, holders supporting said different groups of members respectively and movable to carry them inwardly to wipe the upper over the sole, and means also carried by said holders for automatically applying clamping pressure to said members after they have thus adjusted themselves to the contour of the upper.

28. In a lasting machine, end-lasting means for wiping an upper about an end of a last heightwise of the last and then inwardly over a sole on the last, said end-lasting means comprising two groups of members with the members of each group arranged in a series lengthwise of the edge of the shoe bottom and relatively movable in directions generally parallel to the shoe bottom to adjust themselves to the contour of the upper in wiping it heightwise of the last, holders supporting said different groups of members respectively and movable each about an axis extending heightwise of the last to carry the members inwardly to wipe the upper over the sole, mechanisms on said holders movable to apply clamping pressure to said members after they have thus adjusted themselves to the contour of the upper, and means for operating said mechanisms by the movements of the holders.

29. In a lasting machine, end-lasting means for wiping an upper about an end of a last heightwise of the last and then inwardly over a sole on the last, said end-lasting means comprising two groups of fingers with the fingers of each group extending lengthwise in generally parallel relation to the shoe bottom and arranged in a series along the edge of the shoe bottom in contiguous relation to one another, the fingers of each group being relatively movable lengthwise to adjust themselves to the contour of the upper in wiping it heightwise of the last, holders supporting said different groups of fingers respectively and movable each about an axis extending heightwise of the last to carry the fingers inwardly to wipe the upper over the sole, and mechanisms carried by said holders for automatically applying clamping pressure laterally to said groups of fingers after they have thus adjusted themselves to the contour of the upper.

30. In a lasting machine, end-lasting means for wiping an upper about an end of a last heightwise of the last and then inwardly over a sole on the last, said end-lasting means comprising two groups of fingers with the fingers of each group extending lengthwise in generally parallel relation to the shoe bottom and arranged in a series along the edge of the shoe bottom in contiguous relation to one another, the fingers of each group being relatively movable lengthwise to adjust themselves to the contour of the upper in wiping it heightwise of the last, holders supporting said different groups of fingers respectively and movable each about an axis extending heightwise of the last to carry the fingers inwardly to wipe the upper over the sole, mechanisms including levers on said holders movable to apply clamping pressure laterally to said groups of fingers after they have thus adjusted themselves to the contour of the upper, and means for thus operating said levers in response to the movements of said holders.

31. In a lasting machine, end-lasting means for wiping an upper about an end of a last heightwise of the last and then inwardly over a sole on the last, said end-lasting means comprising two groups of fingers with the fingers of each group extending lengthwise in generally parallel

relation to the shoe bottom and arranged in a series along the edge of the shoe bottom in contiguous relation to one another, the fingers of each group being relatively movable lengthwise to adjust themselves to the contour of the upper in wiping it heightwise of the last, holders supporting said different groups of fingers respectively and movable each about an axis extending heightwise of the last to carry the fingers inwardly to wipe the upper over the sole, mechanisms including levers on said holders movable to apply clamping pressure laterally to said groups of fingers after they have thus adjusted themselves to the contour of the upper, and means supported independently of said holders for engaging said levers thus to operate them in response to the movements of the holders for wiping the upper inwardly over the sole.

32. In a lasting machine, lasting means for wiping an upper heightwise of a last and then inwardly over a sole on the last and for pressing its margin inwardly in upstanding position against a lip or shoulder on the sole, said lasting means comprising a plurality of lasting members arranged in a series lengthwise of the edge of the shoe bottom and relatively movable in directions generally parallel to the shoe bottom to conform to the contour of the upper, yieldable means for urging said members individually in inward directions, said yieldable means being responsive to resistance of the upper to permit the members to adjust themselves to the contour of the upper in wiping it heightwise of the last and also in pressing its margin inwardly against said lip or shoulder, and additional means arranged directly to control said members to cause them to apply greater inward pressure to the upper in pressing its margin against said lip or shoulder than in wiping it heightwise of the last.

33. In a lasting machine, lasting means for wiping an upper heightwise of a last and then inwardly over a sole on the last and for pressing its margin inwardly in upstanding position against a lip or shoulder on the sole, said lasting means comprising a plurality of lasting members arranged in a series lengthwise of the edge of the shoe bottom and relatively movable in directions generally parallel to the shoe bottom to conform to the contour of the upper, yieldable means for urging said members individually in inward directions, said yieldable means being responsive to resistance of the upper to permit the members to adjust themselves to the contour of the upper in wiping it heightwise of the last and also in pressing its margin inwardly against said lip or shoulder, and automatic means for supplementing the force of said yieldable means by frictional control of said members after the wiping of the upper heightwise of the last to increase their inward pressure on the upper in pressing its margin against said lip or shoulder.

34. In a lasting machine, end-lasting means for wiping an upper about an end of a last heightwise of the last and then inwardly over a sole on the last and for pressing its margin inwardly in upstanding position against a lip or shoulder on the sole, said end-lasting means comprising two groups of lasting members with the members of each group arranged in a series lengthwise of the edge of the shoe bottom and relatively movable in directions generally parallel to the shoe bottom to conform to the contour of the upper, holders supporting said different groups of members respectively and movable to carry

the members inwardly about the end of the upper, yieldable means on said holders for urging said members individually in inward directions, said yieldable means being responsive to resistance of the upper to permit the members to adjust themselves to the contour of the upper in wiping it heightwise of the last and also in pressing its margin inwardly against said lip or shoulder, and automatic means controlled by the movements of said holders for subjecting said members to frictional control to cause them to apply greater inward pressure to the upper in pressing its margin against said lip or shoulder than in wiping it heightwise of the last.

35. In a lasting machine, end-lasting means for wiping an upper about an end of a last heightwise of the last and then inwardly over a sole on the last and for pressing its margin inwardly in upstanding position against a lip or shoulder on the sole, said end-lasting means comprising two groups of lasting fingers with the fingers of each group extending lengthwise in generally parallel relation to the shoe bottom and arranged in a series along the edge of the shoe bottom, the fingers of each group being relatively movable lengthwise to conform to the contour of the upper, holders supporting said different groups of fingers respectively and movable to carry them inwardly about the end of the upper, springs on said holders arranged to urge said fingers individually in inward directions, said springs being responsive to resistance of the upper to permit the fingers to adjust themselves to the contour of the upper in wiping it heightwise of the last and also in pressing its margin inwardly against said lip or shoulder, and automatic means on said holders for subjecting said fingers to frictional control after the wiping of the upper heightwise of the last to increase their inward pressure on the upper in pressing its margin against said lip or shoulder.

36. In a lasting machine, end-lasting means for wiping an upper about an end of a last heightwise of the last and then inwardly over a sole on the last and for pressing its margin inwardly in upstanding position against a lip or shoulder on the sole, said end-lasting means comprising two groups of lasting fingers with the fingers of each group extending lengthwise in generally parallel relation to the shoe bottom and arranged in a series along the edge of the shoe bottom in contiguous relation to one another, the fingers of each group being relatively movable lengthwise to conform to the contour of the upper, holders supporting said different groups of fingers respectively and movable each about an axis extending heightwise of the last to carry the fingers inwardly about the end of the upper, springs carried by said holders for urging the fingers individually in inward directions, said springs being yieldable in response to resistance of the upper to permit the fingers to adjust themselves to the contour of the upper in wiping it heightwise of the last and also in pressing its margin inwardly against said lip or shoulder, and automatic means controlled by the movements of said holders for clamping said fingers together to control them frictionally and thereby to cause them to apply greater inward pressure to the upper in pressing its margin against said lip or shoulder than in wiping it heightwise of the last.

37. In a lasting machine, end-lasting means for wiping an upper about an end of a last into lasted position, said end-lasting means comprising two groups of lasting members with the members of

each group arranged in a series lengthwise of the edge of the shoe bottom and relatively movable to conform to different shoe contours, holders each supporting one of said groups of members and each movable relatively to the other with the members thereon to cause the members to operate on the upper, and means for adjustably positioning a variably predetermined plural number of the members of each group in locations for use on a shoe and the rest in idle locations during the lasting operation.

38. In a lasting machine, end-lasting means for wiping an upper about an end of a last into lasted position, said end-lasting means comprising two groups of lasting members with the members of each group arranged in a series lengthwise of the edge of the shoe bottom and relatively movable to conform to different shoe contours, holders each supporting one of said groups of members and each movable relatively to the other with the members thereon to cause the members to operate on the upper, and means for adjustably positioning a variably predetermined number of the members of each group in locations for use on a shoe and the rest in idle locations beyond the shoe lengthwise thereof during the lasting operation.

39. In a lasting machine, end-lasting means for wiping an upper about an end of a last into lasted position, said end-lasting means comprising two groups of lasting members with the members of each group arranged in a series lengthwise of the edge of the shoe bottom and relatively movable to conform to different shoe contours, holders each supporting one of said groups of members and movable with that group about an axis extending heightwise of the shoe to cause the members to operate on the upper, and means on each of said holders for adjustably positioning a variably predetermined plural number of the corresponding group of members in locations for use on a shoe and the rest in idle locations during the lasting operation.

40. In a lasting machine, end-lasting means for wiping an upper about an end of a last into lasted position, said end-lasting means comprising two groups of lasting members with the members of each group arranged in a series lengthwise of the edge of the shoe bottom and relatively movable to conform to different shoe contours, each of said groups of members being movable inwardly toward the shoe to cause the members to operate on the upper and being adjustable lengthwise of the edge of the shoe bottom to position a variably predetermined number of the members in locations for use on a shoe and the rest in idle locations during the lasting operation.

41. In a lasting machine, end-lasting means for wiping an upper about an end of a last into lasted position, said end-lasting means comprising two groups of lasting members with the members of each group arranged in a series lengthwise of the edge of the shoe bottom and relatively movable to conform to different shoe contours, holders each supporting one of said groups of members and each movable relatively to the other with the members thereon to cause the members to operate on the upper, and means for adjusting each group of members relatively to its holder lengthwise of the edge of the shoe bottom to position a variably predetermined number of the members in locations for use on a shoe and the rest in idle locations beyond the shoe lengthwise thereof during the lasting operation.

42. In a lasting machine, end-lasting means for

wiping an upper about an end of a last into lasted position, said end-lasting means comprising two groups of lasting fingers with the fingers of each group extending lengthwise in generally parallel relation to the shoe bottom and arranged in a series along the edge of the shoe bottom, the fingers of each group being relatively movable lengthwise to conform to different shoe contours, and holders each supporting one of said groups of fingers and each movable relatively to the other with the fingers thereon to cause the fingers to operate on the upper, each group of fingers being adjustable relatively to its holder lengthwise of the edge of the shoe bottom to position a variably predetermined number of the fingers in locations for use on a shoe and the rest in idle locations during the lasting operation.

43. In a lasting machine, end-lasting means for wiping an upper about an end of a last into lasted position, said end-lasting means comprising two groups of lasting fingers with the fingers of each group extending lengthwise in generally parallel relation to the shoe bottom and arranged in a series along the edge of the shoe bottom, the fingers of each group being relatively movable lengthwise to conform to different shoe contours, holders each supporting one of said groups of fingers and movable about an axis extending heightwise of the shoe to cause the fingers to operate on the upper, and means for adjusting each group of fingers relatively to its holder lengthwise of the edge of the shoe bottom to position a variably predetermined number of the fingers in locations for use on a shoe and the rest in idle locations beyond the shoe lengthwise thereof during the lasting operation.

44. In a lasting machine, end-lasting means for wiping an upper about an end of a last into lasted position, said end-lasting means comprising two groups of lasting fingers with the fingers of each group extending lengthwise in generally parallel relation to the shoe bottom and arranged in a series along the edge of the shoe bottom, the fingers of each group being relatively movable lengthwise to conform to different shoe contours, holders each supporting one of said groups of fingers and each movable relatively to the other with the fingers thereon to cause the fingers to operate on the upper, each group of fingers being adjustable relatively to its holder lengthwise of the edge of the shoe bottom to position a variably predetermined number of the fingers in locations for use on a shoe and the rest in idle locations beyond the shoe lengthwise thereof during the lasting operation, and means for deflecting the idle fingers of each group lengthwise in inward or outward directions in accordance with the direction of adjustment of the group of fingers.

45. In a lasting machine, end-lasting means for wiping an upper about an end of a last into lasted position, said end-lasting means comprising two groups of lasting fingers with the fingers of each group extending lengthwise in generally parallel relation to the shoe bottom and arranged in a series along the edge of the shoe bottom, the fingers of each group being relatively movable lengthwise to conform to different shoe contours, holders each supporting one of said groups of fingers and each movable relatively to the other with the fingers thereon to cause the fingers to operate on the upper, each group of fingers being adjustable relatively to its holder lengthwise of the edge of the shoe bottom to position a variably predetermined number of the fingers in locations for use on a shoe and the rest in idle

locations beyond the shoe lengthwise thereof during the lasting operation, and spring means into operative relation to which the idle fingers are moved by adjustment thereof in one direction for controlling them in their operation on the shoe.

46. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, the two groups of members being movable relatively to each other as units each about an axis extending heightwise of the shoe to effect the wiping of the marginal portion of the upper inwardly over the sole, a flexible wiping band arranged to extend lengthwise about the end of the shoe along said groups of members between them and the upper to engage the upper in operating on the shoe, and means for holding said band in that relation to said members for use on successive shoes.

47. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, the two groups of members being movable relatively to each other to effect the wiping of the marginal portion of the upper inwardly over the sole, a flexible wiping band arranged to extend lengthwise about the end of the shoe along said groups of members between them and the upper to engage the upper in operating on the shoe, means for anchoring the band in a location substantially at the extreme end of the shoe to position it relatively to said groups of members, and additional means connected to the ends of the band beyond the groups of members further to control it in the wiping operation.

48. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, the two groups of members being movable relatively to each other to effect the wiping of the marginal portion of the upper inwardly over the sole, a flexible wiping band arranged to extend lengthwise about the end of the shoe along said groups of members between them and the upper to engage the upper in operating on the shoe, means for anchoring the band in a location substantially at the extreme end of the shoe to position it relatively to said groups of members, and spring means connected to the ends of the band for pulling them outwardly widthwise of the shoe further to control the band in the wiping operation.

49. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally

parallel to the shoe bottom to conform to different shoe contours, the two groups of members being movable relatively to each other each about an axis extending heightwise of the shoe to effect the wiping of the marginal portion of the upper inwardly over the sole, a carrier supporting said groups of members and relatively to which they are thus movable, said carrier being movable to advance the groups of members lengthwise of the shoe, a flexible wiping band arranged to extend lengthwise about the end of the shoe along said groups of members between them and the upper to engage the upper in operating on the shoe, and means for holding said band substantially midway between its opposite ends in fixed relation to said carrier to position it relatively to said groups of members.

50. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, holders supporting said groups of members respectively and each movable about an axis extending heightwise of the shoe with the members thereon to effect the wiping of the marginal portion of the upper inwardly over the sole, a flexible wiping band arranged to extend lengthwise about the end of the shoe along said groups of members between them and the upper to engage the upper in operating on the shoe, means for anchoring said band in a location substantially at the extreme end of the shoe to position it relatively to said groups of members, and springs connected to the ends of the band and to said holders for pulling the ends of the band outwardly widthwise of the shoe further to control the band in the wiping operation.

51. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, the two groups of members being movable relatively to each other to effect the wiping of the marginal portion of the upper inwardly over the sole, and a flexible wiping band arranged to extend lengthwise about the end of the shoe along said groups of members between them and the upper to engage the upper in operating on the shoe, said band comprising a plurality of resilient strips arranged in superposed relation.

52. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, the two groups of members being movable relatively to each other to effect the wiping of the marginal portion of the upper inwardly over the sole, a flexible wiping band arranged to extend lengthwise about the end of the shoe along said groups of members between them and the upper to engage the upper in operating on the shoe, said band com-

prising a plurality of resilient strips arranged in superposed relation, and means for fastening said strips together in fixed relation to one another only in a location substantially at the extreme end of the shoe.

53. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, the two groups of members being movable relatively to each other to effect the wiping of the marginal portion of the upper inwardly over the sole, and a flexible wiping band arranged to extend lengthwise about the end of the shoe along said groups of members between them and the upper to engage the upper in operating on the shoe, said groups of members being adjustable along the band to position a variably predetermined number of them in locations for use on a shoe and the rest in idle locations during the lasting operation.

54. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, holders each supporting one of said groups of members and each movable relatively to the other with the members thereon to effect the wiping of the marginal portion of the upper inwardly over the sole, and a flexible wiping band arranged to extend lengthwise about the end of the shoe along said groups of members between them and the upper to engage the upper in operating on the shoe, said groups of members being adjustable along the band relatively to their holders to position a variably predetermined number of them in locations for use on a shoe and the rest in idle locations beyond the shoe lengthwise thereof during the lasting operation.

55. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, the two groups of members being movable relatively to each other to effect the wiping of the marginal portion of the upper inwardly over the sole, a flexible wiping band arranged to extend lengthwise about the end of the shoe along said groups of members between them and the upper to engage the upper in operating on the shoe, said groups of members being adjustable along the band to position a variably predetermined number of them in locations for use on a shoe and the rest in idle locations during the lasting operation, the members of each group having slots therein in alignment with one another lengthwise of the edge of the shoe bottom, and projections on the band extending into said slots to assist in supporting the band while permitting the adjustments of the members.

56. In a lasting machine, end-lasting means for wiping an upper about an end of a last into lasted relation to a sole on the last, said end-lasting means comprising two groups of lasting members with the members of each group arranged in a series lengthwise of the edge of the shoe bottom and relatively movable in directions generally parallel to the shoe bottom to conform to different shoe contours, holders each supporting one of said groups of members and each movable relatively to the other with the members thereon to effect the wiping of the marginal portion of the upper inwardly over the sole, a flexible wiping band arranged to extend lengthwise about the end of the shoe along said groups of members between them and the upper to engage the upper in operating on the shoe, means for supporting said band in a location substantially at the extreme end of the shoe, said groups of members being adjustable along the band relatively to their holders to position a variably predetermined number of them in locations for use on a shoe and the rest in idle locations beyond the shoe lengthwise thereof during the lasting operation, the members of each group having slots therein in alignment with one another lengthwise of the edge of the shoe bottom, and projections on the band extending into said slots to assist in supporting the band while permitting the adjustments of the members.

57. In a lasting machine, end-lasting means comprising a flexible band arranged to extend lengthwise about an end of a shoe for engagement with the upper, two groups of members positioned respectively at the opposite sides of the end portion of the shoe with the members of each group arranged in a series along the band for pressing it inwardly against the upper and relatively movable in the lasting operation to conform to the contour of the shoe, and two holders supporting said groups of members respectively and movable relatively to each other to carry the members inwardly about the end of the shoe, said groups of members being adjustable relatively to their holders lengthwise of the band to position a variably predetermined number of the members in locations to act on the band and the rest in idle locations during the lasting operation.

58. In a lasting machine, end-lasting means comprising a flexible band arranged to extend lengthwise about an end of a shoe for engagement with the upper, two groups of members positioned respectively at the opposite sides of the end portion of the shoe with the members of each group arranged in a series along the band for pressing it inwardly against the upper and relatively movable in the lasting operation to conform to the contour of the shoe, two holders supporting said groups of members respectively and movable relatively to each other to carry the members inwardly about the end of the shoe, means for supporting the band independently of said groups of members in a location substantially at the extreme end of the shoe, and additional means connected to the ends of the band for further controlling it, said groups of members being adjustable relatively to their holders lengthwise of the band to position a variably predetermined number of the members in locations to act on the band and the rest in idle locations beyond the shoe lengthwise thereof during the lasting operation.

PHILIP E. BURBY.

CERTIFICATE OF CORRECTION.

Patent No. 2,364,057.

December 5, 1944.

PHILIP E. BURBY.

It is hereby certified that error appears in the printed specification of the above numbered patent requiring correction as follows: Page 3, first column, line 1, for the words "the lip than in the upwiping operation. For this" read --extends downwardly through a straight slot 70--; and that the said Letters Patent should be read with this correction therein that the same may conform to the record of the case in the Patent Office.

Signed and sealed this 13th day of February, A. D. 1945.

Leslie Frazer

(Seal)

Acting Commissioner of Patents.
